UNITED STATES PATENT OFFICE.

CALVIN KEITH AND GEORGE F. LISTER, OF MANSFIELD, OHIO.

HINGE.

SPECIFICATION forming part of Letters Patent No. 788,051, dated April 25, 1905.

Application filed July 1, 1904. Serial No. 214,945.

To all whom it may concern:

Be it known that we, CALVIN KEITH and GEORGE F. LISTER, citizens of the United States, residing at Mansfield, in the county of 5 Richland and State of Ohio, have invented certain new and useful Improvements in Hinges; and we do hereby declare the following to be a full, clear, and exact description of the invention, such as will enable others skilled in 10 the art to which it appertains to make and use the same.

Our invention relates to improvements in universal lock-hinges.

It has for its object to provide a hinge which 15 may be visible or invisible and adapted to be locked or held rigidly in place at different points in its circuit.

The invention consists in the details of construction and combinations of parts herein- 20 described, and more particularly pointed out in the claims concluding this specification.

In the accompanying drawings, illustrating 25 the preferred embodiment of our invention, Figure 1 is an elevation of our hinge applied to a door, the front plate being removed, disclosing the interior mechanism and the outline of the door and frame in dotted lines.

Fig. 2 is a central vertical sectional view 30 through the hinge and supporting device.

Fig. 3 is an elevation showing the mechanism 35 of the hinge when the door is opened to an angle of ninety degrees, parts of the door and frame being broken away; and Fig. 4 is a perspective view of one of the spring-pressed arms or jaws.

Referring more particularly to the drawings, in carrying out our invention we provide a frame 1, adapted to be attached to one of the lower corners of a door, as shown. A 40 disk or plate 2, fixed to a pin 3, is mounted above an opening in said frame, said pin extending through said opening and engaging the floor-plate 4. Said floor-plate has semi-circular raceway 4^a for ball-bearing around 45 its upper edge, and an upper bearing-disk 5, fixed to the frame, has a supplemental groove or raceway 5^a in its lower surface.

To the upper surface of the disk 2, near opposite sides thereof, are mounted roller-sleeves 50 6 around screws 7. If desired, a yoke or cross-

bar 8, secured to the disk 2 at its center and having oppositely-extending arms 9, each projecting above one of said roller-sleeves, may be used or the roller-sleeves with their securing-screws may be arranged separately. 55 Within the rectangular portion of the frame are pivoted two oppositely-facing arms or jaws 10, provided with wide lower ends with vertical grooves 11 about centrally thereof. Said lower ends of said jaws are preferably 60 about as wide from back to front as shown in the drawings as the diameter of the disk 2, so that they will at one position of the door engage both roller-sleeves, as in Figs. 1 and 2. When the door is pushed, as in opening the 65 same, the jaws are forced apart by the roller-sleeves, so that the jaws engage said sleeves separately until the door has been rotated on its pivot or axis one hundred and eighty degrees. The upper ends of said jaws may be 70 smaller and of less width, as shown, and are each preferably provided with a perforation 13 with another smaller opening 12 therein. A spring 14 is arranged between said jaws, having each end inserted through the perforation 13 into the opening or socket 12 of one of said jaws.

It will be readily seen that when the door is opened the lower ends of the jaws will be forced apart by the roller-sleeves until said 80 sleeves engage the central grooves in said jaws, when the door will be locked or held in that position until it is either pushed back to its former position or further around. While we have shown our hinge arranged at one side 85 of the door, so that it can open either way or remain in said closed position, said hinge may be used on revolving doors, in which case the door may be held rigidly at each ninety degrees in its circle of movement. 90

We are aware that changes may be made in our invention without departing from the spirit or sacrificing the advantages thereof. For instance, a different form of spring from that shown—a flat one, for example—may be 95 used, and the form of the jaws or arms may be varied. We therefore reserve the right to make such changes as fairly fall within the scope of our invention.

Having thus described our invention, what 100

we claim as new, and desire to secure by Letters Patent, is—

1. A hinge comprising a frame adapted to be pivotally mounted upon a fixture, a pin having a disk arranged within said frame, said pin extending through said frame and secured to said fixture, oppositely-arranged roller-sleeves on said disk, and spring-pressed jaws adapted to engage either one of said roller-sleeves separately or both at the same time.

2. A hinge comprising a frame adapted to be pivotally mounted upon said fixture, a pin having a disk arranged within said frame, said pin extending through said frame and secured to said fixture, oppositely-arranged pins on said disk, roller-sleeves mounted on said pins, and spring-pressed jaws, each having a centrally-arranged groove adapted to engage said roller-sleeve.

3. A hinge comprising a frame adapted to be pivotally mounted upon the fixture, a pin having a disk arranged within said frame, said pin extending through said frame and secured to said fixture, oppositely-arranged pins on

said disk, roller-sleeves mounted on said disks, jaws pivoted to said frame and each having a perforation with a socket-opening therein, and a spring having each of its extremities extending into the perforation and engaging the 30 socket in one of said jaws.

4. A hinge comprising a frame, a pivotal bearing comprising a floor-plate and a ring secured to said frame, a pin having a disk arranged within said frame, said pin extending through said frame and engaging said floor-plate, oppositely-arranged pins on said disk, roller-sleeves mounted on said pins and spring-pressed jaws adapted to engage either one of said sleeves separately or both at the same time 35 40 whereby the door is held rigidly at different points in the circle of movement.

In testimony whereof we affix our signatures in presence of two witnesses.

CALVIN KEITH.
G. F. LISTER.
